ADJUSTABLE SUPPORT FOR A SPRAY NOZZLE OR THE LIKE

Kenneth M. Daniels, 125 Roberta Drive,
Woodside, Calif. 94062

Filed Mar. 21, 1973, Ser. No. 343,203

Term of patent 14 years

Int. Cl. D8—08

U.S. Cl. D8—72

FIG. 1 is a perspective view of an adjustable support for a spray nozzle or the like showing my new design; and

FIG. 2 is a side elevational view of said support in a different position from that shown in FIG. 1, a portion of the rod being omitted for convenience of illustration.

The broken line representation of a spray system in FIG. 1 is for purposes of illustration only.

I claim:

The ornamental design for an adjustable support for a spray nozzle or the like, substantially as shown and described.
